(57) **CLAIM**

The ornamental design for a sandwich turner, as shown and described.

DESCRIPTION

FIG. 1 is a front perspective view of a sandwich turner showing my new design.

FIG. 2 is a top plan view thereof.

FIG. 3 is a bottom plan view thereof.

FIG. 4 is a right side elevational view thereof.

FIG. 5 is a left side elevational view thereof.

FIG. 6 is a front elevational view thereof; and,

FIG. 7 is a rear elevational view thereof.

In the drawings, the broken lines in FIGS. 1-7 depict portions of the design that form no part of the claim.
